THE NORRIS PETERS CO., PHOTO-LITHO., WASHINGTON, D. C.

UNITED STATES PATENT OFFICE.

ANDREAS GRÖNVALD, OF BROCKTON, MASSACHUSETTS, ASSIGNOR OF ELEVEN-TWELFTHS TO OSCAR F. PETERSON, CHARLES R. ANDERSON, AXEL E. PETERSON, AND CHARLES F. DAHLBORG, OF SAME PLACE.

STEAM-BOILER.

SPECIFICATION forming part of Letters Patent No. 668,816, dated February 26, 1901.

Application filed November 1, 1900. Serial No. 35,172. (No model.)

To all whom it may concern:

Be it known that I, ANDREAS GRÖNVALD, a citizen of the United States, residing at Brockton, in the county of Plymouth and State of 5 Massachusetts, have invented certain new and useful Improvements in Steam-Boilers; and I do declare the following to be a full, clear, and exact description of the invention, such as will enable others skilled in the art to 10 which it appertains to make and use the same.

This invention has relation to improvements in steam-boilers, and particularly to steam-boilers of the fire-tube type.

The object of the invention is to provide a 15 boiler of this character having a novel construction and arrangement of parts whereby a larger proportion than usual of the heat units from the hot air, smoke, and products of combustion rising from the bed of fuel is 20 utilized and a material saving in fuel effected.

According to this invention the hot air, smoke, and products of combustion rising from the bed of fuel on the grate circulate in the usual manner from the fire-box beneath 25 the boiler to the back of the boiler and thence return to the front through the fire-tubes, passing from said tubes into the ordinary smoke box or drum at the front of the boiler; but instead of discharging at this point into 30 the smoke-stack the smoke and gases pass downward through an intervening flue provided for that purpose and thence discharge into the smoke-stack. By this construction the outflow of the smoke and gases is checked 35 or retarded, owing to the disinclination of the same to taking a downward course, and a pressure in the said smoke box or drum is created, resulting in the utilization of a large proportion of the heat ordinarily wasted and 40 a consequent saving in fuel. The flue is provided with a damper or regulator by which the downward and outward circulation of the smoke and gases may be controlled.

In the accompanying drawings, Figure 1 is 45 a vertical longitudinal section of a steam-boiler constructed in accordance with my invention. Fig. 2 is a vertical transverse section of the same on line 2 2 of Fig. 1.

Referring now more particularly to the 50 drawings, the numeral 1 represents a fire-tube

boiler of the horizontal type; 2, the tubes thereof; 3, the boiler casing or setting; 4, the ash-pit, and 5 the fire-box or combustion-chamber, containing the grate 6.

7 is the smoke box or drum at the front of 55 the boiler, into which the smoke and gases from the tubes pass and which ordinarily communicates directly with the smoke-stack.

In accordance with my invention the smoke box or drum 7 is closed at top and is in communication at one side with a downdraft-flue 8, which is provided at a suitable point with a damper or regulator 9 and connects at its lower end with a horizontal draft-flue 10, leading from the ash-pit 4 to the smoke-stack 11. 60 65

12 and 13 are clean-outs located, respectively, at the base of the downdraft-flue and at the base of the smoke-stack.

The operation is as follows: The hot air, 70 gases, smoke, and other products of combustion rising from the bed of fuel on the grate pass along the bottom of the boiler to the rear of the boiler and then back to the front through the fire-tubes 2. On entering the box or drum 7 the smoke and gases instead 75 of discharging, as usual, directly to the atmosphere are checked or retarded, owing to the disinclination of the same to take a downward course. The smoke then being heavier than the hot air descends first and under the 80 pressure or tension of the following hot air which is thereby created is forced downward through the flue 8 and into the flue 10 and discharges to the atmosphere through the smoke-stack 11. By thus checking or retard- 85

ing the circulation of the smoke and gases a large proportion of the heat ordinarily allowed to go to waste is utilized and a material saving in fuel effected, and at the same time a rapid discharge of the smoke and other 90 heavier particles of the products of combustion is insured. The purpose of the flue 10 is to promote the draft at the base of the down-flue 8 and through the ash-pit 4. A rapid discharge of the smoke and gases on entering 95 said flue is thereby provided for. On starting up the boiler a fire may first be made in the ash-pit to force the dead air out of the fire tubes and flues preliminary to starting the regular fire on the grate. To prevent the en- 100

trance of cold air through the flue 10 into the ash-pit at this time, a door 14 is provided, which is closed while the dead air is being driven out and opened when the regular fire 5 on the grate is started.

From the foregoing description, taken in connection with the accompanying drawings, the construction, operation, and advantages of my improvement will be readily understood, and it will be seen that a simple, effective, and comparatively inexpensive device 10 capable of application to boilers already in use is provided.

Having thus fully described my invention, 15 what I claim, and desire to secure by Letters Patent, is—

In a boiler, the combination with the fire-

box and ash-pit, and the boiler provided with the fire-tubes and drum, of a smoke-stack, a downdraft-flue leading from the outlet of the drum, a horizontal draft-flue leading from the smoke-stack to the ash-pit and communicating with said downdraft-flue, a damper in the downdraft-flue, and a door or damper for opening and closing the inlet of said draft-flue to the ash-pit, substantially as described. 20 25

In testimony whereof I have hereunto set my hand in presence of two subscribing witnesses.

ANDREAS GRÖNVALD.
